UNITED STATES PATENT OFFICE.

JOHN F. O'CONNOR, OF CHICAGO, ILLINOIS, ASSIGNOR TO WILLIAM F. MINER, OF CRAZY, NEW YORK.

FRICITION SHOCK-ABSORBING MECHANISM.

Application filed May 5, 1921. Serial No. 400,912.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

One object of the invention is to provide a high capacity shock absorbing mechanism especially adapted for railway draft riggings and wherein are obtained certain release, a graduated smooth action, long life, uniform action at all times, low stresses on all friction elements, and low ultimate or peak load transmitted to the car underframe or other supporting framework.

Another object of the invention is to provide a mechanism of the general character above indicated wherein are employed three groups of cooperating friction elements with a pair of wedging or pressure-creating systems interposed between each two groups of cooperating friction elements.

A still further object of the invention is to provide a mechanism wherein are employed three separated groups of cooperating friction elements leaving two spaces therebetween in each of which spaces is provided a wedging or pressure-creating system, each system consisting of a plurality of relatively movable wedge elements with anti-friction means therebetween and anti-friction means between each element and the corresponding adjacent group of friction elements.

Other objects of the invention will more clearly appear from the description herein-after following.

In the drawings forming a part of this specification, Figure 1 is a horizontal, longitudinal sectional view of a portion of a railway draft rigging showing my improvements in connection therewith. Figure 2 is a vertical, transverse, sectional view corresponding substantially to the section line 2-2 of Figure 1. Figure 3 is an enlarged vertical sectional view of the shock absorbing mechanism proper and corresponding to the line 3-3 of Figure 1. Figure 4 is a

vertical, longitudinal, sectional view, parts being broken away, the section corresponding to the line 4-4 of Figure 3. And Figures 5, 6, and 7 are detail perspectives of two different wedge elements and one of the stationary friction plates, respectively.

In said drawings, 10-10 denote channel draft sills of a railway car to the inner faces of which are secured front stop lugs 11 and rear stop lugs 12, the same being of any desired form. The inner portion of a draw-bar is indicated at 13, the same being operatively associated with the shock absorbing mechanism proper by means of a hooded cast yoke 14 and coupler key 15. The yoke 16 and parts therewithin are supported in operative position by a detachable saddle plate 17.

The improved shock absorbing mechanism proper, as shown, comprises, broadly, a column-load-sustaining member A; twin arranged springs B-B; a front rigid follower C; a spring follower D; a series of centrally disposed relatively stationary friction plates E-E; a pair of outer relatively stationary friction plates F-F, a plurality of centrally disposed relatively movable friction plates G-G; a pair of outer relatively movable friction plates H-H; a wedging system on each side of the center line, each consisting of a wedge element J and another wedge element K; an anti-friction roller L between each pair of wedge elements J and K; an anti-friction pad M between each outermost wedge element K and adjacent friction plate H; and retaining bolts N-N.

The column-load-sustaining member A, as shown, is preferably in the form of a malleable casting having top and bottom horizontally extending walls 17-17, a vertical integral rear wall 18 functioning as a follower in conjunction with the stop legs 12 and vertical side walls 19-19 at the forward end of the column A, the length of said side walls 19 being considerably less than the over-all length of the member A so as to leave the sides of the member A open for the insertion and removal of the follower D and springs B. With the construction shown, it will be evident that the forward portion of the member A constitutes, in effect, a hollow rectangular casting or container.

The inner face of each side wall 19 is recessed as indicated at 20 so as to receive a correspondingly formed friction plate or 110

liner F, it being understood that the inner face of each plate F constitutes a friction surface extending parallel to the center line of the mechanism. Directly cooperable with each stationary friction plate F is a movable rectangular friction plate H which is sufficiently elongated so that its forward or outer end extends beyond the end of the member A and into close proximity of the follower 10 C, in normal position of the parts.

At the center, within the casing portion thereof, the member A is recessed on its upper and lower walls as indicated at 21—21 in Figure 3 and in said recessed portions 15 21 are provided transversely extending front flanges 22—22, intermediate transversely extending ribs 23—23 and rear transversely extending ribs 24—24. The flanges 22 provide rearwardly facing shoulders and the ribs 23 and 24 provide forwardly facing shoulders cooperating respectively with the forwardly facing shoulders 122 and rearwardly facing shoulders 124 of the central series of stationary 25 friction plates E. With this construction it is evident that the plates E are held against movement longitudinally relatively to the member A but are responsive to laterally applied pressure.

30 The central series of movable friction plates G are preferably flat rectangular plates of the same character as the outer movable friction plates H. The plates G are intercalated and preferably alternated 35 with the stationary friction plates E, there being one more movable plate G than stationary plate E so as to bring the outermost plates movable as clearly appears from Figures 1 and 3. The stationary plates E 40 are of generally I-cross section so as to thereby provide suitable guiding grooves or channels 25 for the plates G. The depth of said grooves 25 and the thickness of the plates G are so proportioned as to leave 45 spaces 26 between the thickened edges of the plates E. The central stationary plate E is made somewhat thicker than the two side plates E, as shown in Figure 3, in order to provide upper and lower longitudinally extending grooves 27—27 to accommodate the 50 retainer bolts N.

The follower C is of rectangular form and preferably, on its inner face, is provided with a hardened plate insert 28 against 55 which the wedge elements J bear and also the outer ends of the plates G and H, after the follower C has moved a half inch or so relatively to the member A, as hereinafter described.

60 The spring follower D is laterally extended so as to provide bearings for the forward ends of both of the twin springs B and preferably the member A will be notched on each side thereof as indicated at 65 29 to accommodate the extreme edges of the

follower D and permit the rear face of the latter to lie substantially flush with the inner vertical edges of the side walls 19. On its forward side, the follower D is provided with two laterally spaced projections 30—30 70 which straddle the centrally disposed group of intercalated friction plates and extend loosely between the central group and the respective side groups of friction plates. The forward end of each extension 30 is 75 formed with a flat transversely extending bearing face 31 against which rests and bears the corresponding adjacent transverse face 32 of the wedge element K. It will be noted from an inspection of Figure 1 80 that the inner face of all of the relatively movable plates G and H normally bear against the follower D.

The wedging system in each space between the central group of friction elements 85 and corresponding side group, consists of the two wedge elements J and K, as hereinbefore mentioned. Each element K, in addition to its transverse bearing face 32 is provided on its inner side with a wedge roll 90 seat 33 inclined to the axle of the mechanism, a roll stop shoulder 34 being formed at the end of the roll seat in order to assist in holding the roller L in proper position. On its outer side, each element K extends 95 parallel to the center line of the mechanism and in order to reduce the possible friction between each element K and corresponding friction plate H, anti-friction means in the form of an anti-friction pad 100 insert 35 is employed. Each insert may be of any suitable so-called anti-friction material such as phosphor-bronze. The inserts 35 are preferably applied to the members K by forming the latter with undercut dove-tailed grooves and sliding the inserts 35 longitudinally within said grooves, as indicated in Figures 1 and 6. Each wedge member J is formed at its outer end with a transversely extending bearing surface 36 which 105 engages the inner face of the front follower C. The inner side of each member J extends parallel to the center line of the mechanism and in order to reduce the possible friction between the members J and 110 the central group of friction plates, anti-friction pads or inserts 37 are applied to the members J, said pads or inserts being of the same material and form as the inserts 35. In this connection, it will be noted 115 that the active faces of the pads 35 and 37 project outwardly beyond the adjacent parallel faces of the wedge elements so as to insure the bearing taking place on the pads and not on the main portions of the wedge 120 elements J and K. On its outer side, each element J is formed with a wedge roller seat 38 arranged parallel to the corresponding roller seat 37 and a corresponding roller stop shoulder 39 is formed at the inner end 125 130

of the roller seat 38. With this arrangement it will be observed that the two elements J and K of each system are allowed relative movement and such movement is of an anti-friction character because of the interposed rollers L. It will further be observed that each system is anti-frictionally mounted with respect to the respective groups of friction plates on either side thereof, thus rendering the device extremely sensitive both in the setting up of the wedging action during compression and in relieving said wedging pressure during the release.

15 The operation of the device is as follows, assuming an inward or buffing movement of the drawbar. As the drawbar moves inwardly, the follower C is moved uniformly therewith, thus forcing the wedge elements J longitudinally inwardly of the member A, the latter acting as a column-load-sustaining member and follower in conjunction with the rear stop lugs 12. Because of the space normally left between the outer ends 25 of the plates G and H, a space approximating $\frac{1}{2}$ ", none of said plates G or H will be moved during the first part of the movement of the follower C. As the wedge elements J are forced inwardly, they in turn tend to move relatively longitudinally of the wedge elements F which are resisted by the springs B reacting through the follower D. The wedging or lateral-pressure-creating action is thus immediately instituted, 30 forcing the movable and stationary friction plates of all three series into tight frictional contact, the central group of plates being pressed from both sides inwardly toward the central line of the mechanism, as will be understood. The inward movement transmitted to the wedge elements K obviously forces the follower D inwardly against the yielding resistance of the springs B and thus the follower D is removed from contact 35 with the inner ends of the movable friction plates G and H. At the end of the initial action of the compression stroke above described, the follower C engages with the plates G and H and the latter are then forced longitudinally in unison with the follower C and the wedging systems. At this point it will be noted that, at the time the friction plates G and H are first set in motion, the wedging or pressure action will 40 have been imposed thereon so that the desired degree of friction between the movable and stationary plates is thereafter present for the remainder of the compression stroke. The end of the compression stroke, 45 is determined by the follower C engaging with the member A.

Upon removal or discontinuance of the actuating force, the springs B immediately start to expand and thereby force the follower D outwardly or toward the left as

viewed in Figure 1. This action is unopposed by any of the friction plates for the reason that the follower D has been moved out of contact therewith, as previously explained. Consequently, the elements of each wedging system are not only free to move in a releasing direction relatively toward each other but each system may be easily pushed outwardly with respect to the various groups of friction plates under the influence of the follower D. The initial release action just described obviously relieves the pressure on the friction elements and continues until the follower D engages the inner ends of the movable friction plates G and H. Thereafter, the continued outward movement of the follower D under the influence of the springs B, forces the plates G and H back to their normal condition and all of the parts are restored ready for the second compression stroke.

On account of the large number and area of the cooperating friction surfaces, the pressure exerted on each friction plate may be very materially reduced compared to the pressure required on cooperating friction surfaces in many types of friction gears now on the market, thus promoting long life of the parts. It will be observed also that all minor shocks such as are constantly occurring during a relatively steady movement of a train of cars, may be absorbed in the initial half inch movement of the follower C without necessitating any action of the friction plates. Inasmuch as said minor shocks encountered in the operation of cars are so very much more numerous than moderate or heavy shocks, it will be appreciated that the life of the mechanism is very greatly lengthened because of the fact that the friction plates are not brought into play except comparatively infrequently. All of the friction plates may be manufactured in quantity at comparatively small expense and are easily renewed thus minimizing the cost of maintaining the mechanism.

I have herein shown and described what I now consider the preferred manner of carrying out my invention but the same is merely illustrative and I contemplate all changes and modifications that come within the scope of the claims appended hereto.

I claim:

1. In a friction shock absorbing mechanism, the combination with a casting having a hollow casing at one end, a follower wall at the other end and an intermediate spring cage, said casing being provided on the interior thereof on each side with a longitudinally extending friction surface; of a spring resistance disposed within said cage; a plurality of friction plates disposed centrally within said casing and anchored against longitudinal movement with respect thereto but responsive to lateral pressure; a plurality

of relatively movable longitudinally extending friction plates cooperable with said centrally disposed plates and said side friction surfaces of said member, there being 5 spaces left between the central group of friction plates and the side plates; a spring follower within said member interposed between the spring resistance and the inner ends of said movable friction plates normally engaging the latter; a wedging system 10 on each side of the central group of friction plates, each wedging system cooperating with the central group and an outside group of friction plates, each wedging system including, a pair of oppositely arranged wedges, one of said wedges engaging the spring follower and the other extending outwardly slightly beyond the outer edges of the movable friction plates; and an 15 outer follower normally engaging the outer ends of said outermost wedges and slightly spaced from the outer ends of the movable friction plates.

2. In a friction shock absorbing mechanism, the combination with a column-load-sustaining member having a plurality of longitudinally extending friction elements relatively immovable longitudinally of said member; of relatively longitudinally 20 movable friction elements cooperable with said first named elements, the stationary and movable friction elements being divided into three groups with spaces between the central group and each outer group; a spring resistance; an outer follower movable relatively toward and from said member; and a lateral pressure-creating system in each of 25 said spaces cooperable with said groups of friction elements.

3. In a friction shock absorbing mechanism, the combination with a column-load-sustaining member having a plurality of longitudinally extending friction elements relatively immovable longitudinally of said member; of relatively longitudinally 30 movable friction elements cooperable with said first named elements, the stationary and movable friction elements being divided into three groups with spaces between the central group and each outer group; a spring resistance; an outer follower movable relatively toward and from said member; a lateral pressure-creating system in each of 35 said spaces cooperable with said groups of friction elements.

4. In a friction shock absorbing mechanism, the combination with a column-load-sustaining member having a plurality of longitudinally extending friction elements relatively immovable longitudinally of said member; of relatively longitudinally 40 movable friction elements cooperable with said first named elements, the stationary and movable friction elements being divided into three groups with spaces between the central group and each outer group; a spring resistance; an outer follower movable relatively toward and from said member; a lateral pressure-creating system in each of 45 said spaces cooperable with said groups of friction elements.

5. In a friction shock absorbing mechanism, the combination with a column-load-sustaining member having a plurality of longitudinally extending friction elements relatively immovable longitudinally of said member; of relatively longitudinally 50 movable friction elements cooperable with said first named elements, the stationary and movable friction elements being divided into three groups with spaces between the central group and each outer group; a spring resistance; an outer follower movable relatively toward and from said member; a lateral pressure-creating system in each of 55 said spaces cooperable with said groups of friction elements, said systems reacting at one end against said outer follower and at the other end against the spring resistance, each of said pressure-creating systems com-

prising a pair of oppositely arranged relatively movable wedge elements.

4. In a friction shock absorbing mechanism the combination with a column-load-sustaining member having a plurality of longitudinally extending friction elements relatively immovable longitudinally of said member; of relatively longitudinally movable friction elements cooperable with said first named elements, the stationary and movable friction elements being divided into three groups with spaces between the central group and each outer group; a spring resistance; an outer follower movable relatively toward and from said member; a spring follower disposed between said groups of friction elements and the spring resistance; a lateral pressure-creating system in each of 60 said spaces, each system being interposed between the outer follower and the spring follower, and cooperating with the central and one outside group of said friction elements; and anti-friction means interposed between each of said pressure-creating systems and the two corresponding groups of friction elements on either side thereof.

5. In a friction shock absorbing mechanism, the combination with a column-load-sustaining member having a plurality of longitudinally extending friction elements relatively immovable longitudinally of said member; of relatively longitudinally movable friction elements cooperable with said first named friction elements, the stationary and movable friction elements being divided into three groups with spaces between the central group and each outer group; a spring resistance; an outer follower movable relatively toward and from said member; a spring follower disposed between said groups of friction elements and the spring resistance; a lateral pressure-creating system in each of 65 said spaces, each system being interposed between the outer follower and the spring follower and cooperating with the central and one outside group of said friction elements, each of said pressure-creating systems comprising a pair of oppositely arranged and relatively movable wedge elements; and anti-friction means interposed between each pair of said wedge elements.

In witness that I claim the foregoing I have hereunto subscribed my name this 22nd day of April, 1921.

JOHN F. O'CONNOR.
